UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Application filed July 13, 1923. Serial No. 651,298.

To all whom it may concern:

Be it known that I, ARTHUR E. SMALL, residing at Chicago, county of Cook, State of Illinois, and being a citizen of the United States, have invented certain new and useful Improvements in Uncoupling Devices for Car Couplers, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

This particular invention relates to what is generally known in the art as a rotating type of uncoupling device for car couplers and comprises a lever revolvably mounted on the car with brackets or in any other convenient manner, which rod is usually bent downwardly at the outer end to form a handle, and is bent outwardly at its inner end to form a crank, projecting over the coupler which crank is provided with a horizontally positioned eye over the coupler lock lifter. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the eye on the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without becoming disengaged from each other or from either the coupler or the operating rod. It is frequent-

ly necessary to uncouple cars when they are coupled together so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. (See Fig. 3.) The operating rod, as above described, is old and in use on hundreds of thousands of cars now in existence. Such rods had a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked and either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. The device is designed so that the component parts cannot become disconnected from each other or from the operating lever or the coupler. The connection between the component parts and also their connections to the operating rod and the coupler are such that the device cannot become "kinked". Formerly when a brakeman wanted a small chain to repair one of the old connections he simply guessed as to the amount of chain required and applied it to the car, which accounts for the number of "too long" and "too short" chains reported by the commission. This is not possible with my device.

Another object of the invention is to provide a device wherein the component parts are duplicates, therefore, interchangeable. Duplication, of course, also simplifies manufacture, handling, accounting, etc.

Another object is to obtain a device wherein the component parts are duplicates so that they cannot be wrongfully applied to the car or to each other.

Another object, and an important one, is

2
to obtain a connecting device that can be simply, economically and conveniently applied to the old operating rod now on the equipment and to the standard coupler without altering either one whatsoever.

The railroads cannot afford, under present conditions, to scrap and replace these operating rods.

In the drawings:

10 Fig. 1 is a perspective view of a portion of a car with my invention applied thereon.

Fig. 2 is a cross section along line 2—2 of Fig. 1 showing the device in full lines in normal position and in dotted lines in an elevated position.

Fig. 3 is a section along line 2—2 of Fig. 1 showing the device with the coupler in "lock set" position.

20 Fig. 4 is a section along line 2—2 of Fig. 1 showing the device wherein the operating rod is allowed to fall close to the lock lifter.

Fig. 5 is an enlarged side elevation of the device showing the two component members assembled.

25 Fig. 6 is a front elevation of Fig. 5.

Fig. 7 is a blank formed by shearing it out of a flat piece of metal.

Fig. 8 is a side elevation of Fig. 7.

30 Fig. 9 shows the complete member wherein in the eyes have been slit and deflected to form open hooks.

Fig. 10 is a side elevation of Fig. 9.

Fig. 11 is an end elevation of Fig. 9.

The usual parts of the car are shown 35 wherein 1 is the end sill; 2 the push pole pocket; 3 the striking casting; 4 the carry iron; 5 the coupler; 6 the coupler knuckle; 7 the knuckle pivot pin and 8 the lock lifter eye. The rod 9 is revolvably mounted 40 in brackets 10 and 11 which are secured to any convenient part of the car. The rod 9 is bent downwardly at the outer end to form handle 12 and bent laterally at the inner end to form crank 13 which is provided with horizontally disposed eye 14. The duplicate members 15 and 16 being connected together form an operative connection 45 between the lock lifter eye 8 and crank eye 14.

50 The eye of the lock lifter 8 and the eye of the crank arm 14 have their axes substantially parallel, therefore, the axes of the eyes or hooks of my device must also be parallel. This is accomplished by twisting 55 or forming the opposite ends of each individual member in planes substantially forty-five degrees apart. The members are duplicates in every detail so that no matter which ends of the members are connected together 60 the eyes at the opposite ends of the assembled device will be parallel (that is when assembled on the car). The two members may be secured together either at the factory or at the car; in either event it is immaterial which end of the assembled device

is attached to the coupler; in other words, the assembled device cannot be improperly applied to the car.

In Fig. 2 wherein the device is shown in normal position the two members are shown 70 at a slight angle to each other so that the coupler can assume the various service positions without affecting the crank arm.

The members are formed by shearing a blank (see Figs. 7 and 8) from a flat piece 75 of steel or other metal. In the second operation the closed eyes are split, as shown in lines 20 and 21 in Fig. 9, and in the third operation the eyes at the opposite ends of the member are deflected, as shown by lines 80 22 and 23 in Figs. 10 and 11, to form open hooks. While I have described the manufacture as comprising three operations it is understood that all of these operations may be performed by one operation of the machine.

In assembling the members together the adjacent hooks are closed to form eyes and in attaching the device to the crank arm and the lock lifter at the opposite ends, the hooks at the opposite ends are closed to form eyes so that the device cannot become disconnected.

I claim:

1. In an uncoupling device for car couplers comprising a rotatable rod having a handle at its outer end and a crank at its inner end provided with a horizontally positioned eye, and a pair of duplicate members flexibly connecting said eye to said coupler, each of said members having an eye at each end, the axes of said eyes positioned substantially forty-five degrees apart. 95

2. In combination with an uncoupling device for car couplers comprising a rotatable operating rod having a handle at its outer end and a crank at its inner end provided with a horizontally positioned eye, a car coupler equipped with a lock pin provided with a horizontally positioned eye, and a pair of symmetrical and duplicate members provided with split openings at their extremities for engagement with each other and with the eye of said operating rod and the eye of said lock pin. 105

3. In combination with an uncoupling device for car couplers comprising a rotatable operating rod having a handle at its outer end and a crank at its inner end provided with a horizontally positioned eye, a car coupler equipped with a lock pin provided with a horizontally positioned eye, and a pair of duplicate members symmetrical with respect to center lines across their width and length, each of said members provided with split openings at their extremities for engagement with each other and with the eye of said operating rod and the eye of said lock pin. 110

4. In combination with an uncoupling de- 125

vice for car couplers comprising a rotatable operating rod having a handle at its outer end and a crank at its inner end provided with a horizontally positioned eye, a car 5 coupler equipped with a lock pin provided with a horizontally positioned eye, and a pair of symmetrical and duplicate members provided with split openings at their extremities for engagement with each other 10 and with the eye of said operating rod and the eye of said lock pin, the axes of said openings positioned substantially forty-five degrees apart in each link.

5. In combination with an uncoupling device for car couplers comprising a rotatable operating rod having a handle at its outer end and a crank at its inner end provided with a horizontally positioned eye, a car 15 coupler equipped with a lock pin provided with a horizontally positioned eye, and a pair of symmetrical and duplicate members provided with split openings at their extremities for engagement with each other 20

and with the eye of said operating rod and the eye of said lock pin, the axes of said 25 openings positioned substantially forty-five degrees apart in each link; the axes of the openings at the extremities of said connected members being substantially parallel when in operative position.

6. In combination with an uncoupling device for car couplers comprising a rotatable operating rod having a handle at its outer end and a crank at its inner end provided with a horizontally positioned eye, a car 30 coupler equipped with a lock pin provided with a horizontally positioned eye, and a pair of bars or plates with openings at their ends, the marginal metal forming said openings being split and struck away from the 35 plane of the opening forming means to connect one to another and to the eyes of said operating rod and lock pin, and when said openings are closed forming complete loops in a single plane.

ARTHUR E. SMALL.
